US0D1040146S

(12) **United States Design Patent** (10) **Patent No.:** **US D1,040,146 S**
(45) **Date of Patent:** **** Aug. 27, 2024**

(54) **CASE FOR ELECTRONIC COMMUNICATIONS DEVICE**

(71) Applicant: **SPIGEN KOREA CO., LTD.**, Seoul (KR)

(72) Inventor: **Tae Sung Yoon**, Seoul (KR)

(73) Assignee: **SPIGEN KOREA CO., LTD.**, Seoul (KR)

(**) Term: **15 Years**

(21) Appl. No.: **29/866,557**

(22) Filed: **Sep. 19, 2022**

(51) **LOC (14) Cl.** **03-01**

(52) **U.S. Cl.**

USPC **D3/218; D3/249**

(58) **Field of Classification Search**

(57) **CLAIM**

The ornamental design for a case for electronic communications device, as shown and described.

DESCRIPTION

FIG. 1 is a front perspective view of the case for electronic communications device showing my new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines throughout the drawing figures depict portions of the case for electronic communications device that form no part of the claimed design. The broken lines and regions bounded by broken lines form no part of the claimed design.

1 Claim, 7 Drawing Sheets
